[57] CLAIM

The ornamental design for a support for a handle unit, as shown and described.

DESCRIPTION

FIG. 1 is a perspective view taken from the top, front and right side of a support for a handle unit showing my new design;

FIG. 2 is an enlarged top plan view thereof;

FIG. 3 is an enlarged left side elevational view thereof;

FIG. 4 is an enlarged right side elevational view thereof;

FIG. 5 is an enlarged front elevational view thereof;

FIG. 6 is an enlarged rear elevational view thereof;

FIG. 7 is an enlarged bottom plan view thereof; and,

FIG. 8 is a perspective view of a second embodiment of the design of FIG. 1, the only difference being its mirror image configuration.

The fragmentary broken line representations of doors, escutcheons, and handles in FIGS. 1 and 8 are for illustration only, and form no part of the claimed design.
